[57] **CLAIM**

The ornamental design for the catch retainer for a vehicle sun roof panel, as shown and described.

DESCRIPTION

FIG. 1 is a bottom plan view of a catch retainer for a vehicle sun roof panel showing my new design;

FIG. 2 is a top plan view thereof;

FIG. 3 is a right-end elevational view thereof;

FIG. 4 is a top front perspective view thereof;

FIG. 5 is a left-end elevational view thereof;

FIG. 6 is a front elevational view thereof and;

FIG. 7 is a rear elevational view thereof.

The characteristic feature of my design resides in the raised outer wall and central wall formed on the top surface thereof as best illustrated in FIG. 4 of the drawings.
